FABRIC FOR SEAT COVERINGS.

No. 16,051.

Patented Apr. 21, 1885.

UNITED STATES PATENT OFFICE.

JOSEPH HODGSON, OF PHILADELPHIA, PENNSYLVANIA.

DESIGN FOR A FABRIC FOR SEAT-COVERINGS.

SPECIFICATION forming part of Design No. 16,051, dated April 21, 1885.

Application filed March 2, 1885. Term of patent 14 years.

To all whom it may concern:

Be it known that I, JOSEPH HODGSON, a citizen of the United States, residing at Philadelphia, in the county of Philadelphia and State of Pennsylvania, have invented and produced a new and original Design for an Upholstery Fabric for Seat-Coverings; and I do hereby declare that the photographic print accompanying this specification conveys to any one skilled in the art a clear understanding of the same, and is sufficient to enable such person to use my invention.

The leading features of my design are: Near the center of the design is shown a representation of a fruit, such as an unhulled nut; at other parts shows smaller representations, which are buds. Below the nut, both on the right and left, are shown representations of blossoms in full bloom. At the lower part of the design the branch is represented in form of a scroll.

What I claim as my invention, and desire to secure by Letters Patent, is—

The design for an upholstery fabric for seat-coverings, as shown in the photographic print and described in the specification.

JOSEPH HODGSON.
